UNITED STATES PATENT OFFICE.

JAMES SERENY, OF WHITE PLAINS, NEW YORK.

HAIRPIN.

Application filed June 16, 1923. Serial No. 645,847.

To all whom it may concern:

Be it known that I, JAMES SERENY, a citizen of the United States, residing at White Plains, in the county of Westchester and 5 State of New York, have invented certain new and useful Improvements in Hairpins, of which the following is a specification.

This invention relates to hair pins and more particularly to a novel and improved 10 crimping construction wherein the strands of hair may be locked and will otherwise prevent the loss of the pin when once inserted in the hair.

One of the objects of my invention is to 15 provide a crimped hair pin wherein the extremities are bent inwardly toward each other and securely fastened, thus permitting the hair to be locked therebetween and in addition, avoiding the objectionable pointed 20 ends of the common type of hair pin now in use.

A further object of my invention is to provide a hair pin bent in a spiral or sinuous form throughout a portion of its length and 25 designed so that the ends of the wire are brought together and securely fastened at the bight end of the pin thus constituting a clamping or fastening means when the strands of hair intertwine the hair pin.

To enable others skilled in the art to fully 30 comprehend the underlying features of my invention that they may embody the same in the various modifications in structure and relation contemplated, drawings depicting 35 a preferred form have been annexed as a part of this disclosure and in such drawings, similar reference characters denote corresponding parts throughout all the views, of which,

Figure 1 is a perspective view of the assembled hair pin.

Figure 2 is an enlarged detail showing the clamping means for the ends of the wire.

Figure 3 is a view taken on the line 3—3 45 of Figure 2.

Figure 4 is a section taken on the line 4—4 of Figure 1.

Figure 5 is a further section taken on the line 5—5 of Figure 1.

Figure 6 is an enlarged detail of a modified form of clamping means for the ends of the wire.

Figure 7 is a view of the blank of the modified form of fastening means shown in 55 Figure 6.

Figure 8 is a still further modified form of fastening means.

Figure 9 is a view of the blank shown in the modified form of Figure 8.

Figure 10 is a view of the blank before it is bent and shaped, and

Figure 11 is a still further modified form of means for fastening the ends of the wire.

Referring now to the drawings wherein like reference characters designate corresponding parts throughout the several views, 65 5 designates the bight or curved top of the hair pin formed by the angularly disposed sides 6, 7, of a continuous length of wire, which sides are crimped in the form of a 70 spiral or in a sinuous manner as indicated at 8 throughout a portion of their length, as clearly shown by Figure 1 of the drawings. The sides 6, 7, are also curved at their lower extremities as indicated by numeral 9 and 75 are bent inwardly toward each other, thus avoiding the sharp points common to hair pins. The extreme ends of the wire 10, 11, are bent inwardly toward each other and are of a length so that the extremities or terminals 80 lie adjacent the bight portion 5. In the form of the clamp or retaining device shown by Figures 6 and 7, I have provided a substantially T-shaped blank 15 which is rolled over on itself so as to engage the bight portion 85 5, above referred to, and lock the same by crimping or otherwise as the arms 16, 17 of the blank are rolled around the extremities or terminals in the manner shown more clearly by Figure 6 of the drawings. 90

It will thus be seen from this construction of the hair pin that when the strands of hair enter between the spirals and the straight portion of the wire that the hair will be practically clamped or tightly gripped into 95 the resiliency of the said extremities, held by the clamping plate 15 above referred to. This not only prevents the hair pin from falling out but is extremely safe since the point ends are avoided.

As a further embodiment of a clamping means for the ends of the wire, I may also use a blank as indicated generally by numeral 20, having segmental cut-out portion 21 in the edges thereof so that when the 105 blank is bent over on itself as at 22, the ends of the wire may be gripped by the edges of the blank when bent in the form shown by Figure 8 of the drawings. The central portion of the blank is recessed as indicated at 110

23 whereby a proper shaping of the blank will conform to the curvature of the bight portion 5 as is well understood. As a further modification, the ends may be wrapped 5 about the bight portion 5 and intertwined so as to properly secure the free ends of the wire to the bight portion.

While I have illustrated and described my invention with some degree of particularity, 10 I realize that in practice various alterations therein may be made. I therefore reserve the right and privilege of changing the form of the details of construction or otherwise altering the arrangement of the correlated 15 parts without departing from the spirit of the invention or the scope of the appended claims.

Having thus described my invention, what I claim as new, and desire to secure by 20 United States Letters Patent is:

1. A hair pin consisting of a wire bent in-

termediate of its ends forming angularly disposed legs, said legs being bent inwardly toward each other so that the extremities of the wire extend adjacent the intermediate 25 bend therein, a portion of each of said legs being bent in the form of a spiral and means for securing the free ends of the wire to said intermediate bent portion.

2. A hair pin consisting of a single strip 30 of wire bent intermediate of its ends forming angularly disposed legs, said legs being bent to provide rounded ends and having their extremities extending to a point adjacent the intermediate bend, a portion of the 35 length of each of said legs being bent in the form of a spiral, so as to clamp the hair and means for securing the free ends of the bent legs to the intermediate bend in the wire.

In testimony whereof I affix my signature:

JAMES SERENY. [L. S.]
